FURNITURE BRACE

Salvatore Di Grado and Charles C. Greco,
Philadelphia, Pa.

Application November 13, 1943, Serial No. 510,254

3 Claims. (Cl. 155—197)

This invention relates to braces for articles of furniture supported by legs while it has more particular reference to chairs, tables, beds and analogous things, the legs of which are liable to become loose and unstable when subjected to hard use.

While not so restricted this invention is preferably adapted for application to chairs, tables and similar articles the legs of which are liable to work loose at their junctures with the seat or top, as well as at their socket connection to the rungs, with incidental spreading or separation of such parts, whereby said articles become unstable and unsafe.

The primary object of this invention is to provide a furniture-brace for restoring the relatively separated or displaced legs of chairs, tables and other articles of furniture, to normal rigid service position.

Another object is the provision of a brace of the indicated species including structural refinements whereby its action is more effective, while undue straining of one leg relative to another, or the others, is positively prevented.

A further object is the provision of a reinforcing brace for chairs, tables and other articles of furniture that is readily applied and which in no respect mars the appearance of the article of furniture when so applied.

A still further object is the provision of a furniture-brace of the above indicated type which is simple to construct, inexpensive to manufacture, and withal highly effective for the purpose had in view.

Other objects, with ancillary advantages, will become apparent to those conversant with the art upon a consideration of the construction, arrangement and combination of parts, involved in the means hereinafter disclosed; while it will also be appreciated that the invention is susceptible of other embodiment and adaptation, or structurally modified form, coming equally well within the terms and scope of the concluding claims.

In the drawing:

Fig. I is a plan section taken just below the seat of a standard type four-leg chair, and illustrating the application thereto of a preferred form of the novel brace hereinafter fully explained.

Fig. II is a detail view of one of the leg-engaging fabric straps.

Fig. III is a fragmentary view corresponding with the upper portion of Fig. I but including a modified form of the leg-engaging straps; and,

Fig. IV is a similar view to Fig. II of the modified form of leg-engaging strap.

In describing the forms of this invention exemplified by the above mentioned drawing, specific terms will be employed for the sake of clarity, but it is to be distinctly understood the scope of said invention is not thereby limited, each such term being intended to embrace all equivalents which perform the same function for an analogous purpose.

Referring now with greater particularly to Figs. I and II of the drawing, the four legs 5 of a standard type of chair are normally rigidified by conventional rungs 6 appropriately fitted in sockets therein, in accordance with known practice. These parts constitute no feature of the present invention and are merely referred to by way of affording a clear basis in explaining the furniture brace of said invention, such brace being comprehensively designated 7.

The brace 7 comprises a draw-screw device or turn-buckle 8 with eye-bolts or screws 9 through each of which passes an obtuse-angled tie-rod 10, of rigid character and predetermined diameter. These tie-rods 10 are complementary and each is conveniently shaped to include a median angle 11 of approximately one-hundred-and-twenty degrees, and has the ends bent to define opposingly-directed terminal-hooks 12 respectively including an angle of about sixty-degrees or half that of said median angle.

Engageable by the terminal-hooks 12 of the respective tie-rods 10 are straps 13, preferably of "sail" or analogous type cloth, having metal eyelets or grommets 14 proximate the ends thereof, such grommets being of a size and character for easy application to the terminal-hooks 12 as readily understandable on an examination of Figs. I and II. Attention is particularly directed to the fact that the relatively inner eyelets or grommets 14 in use invariably seek the crotch of the hooks 12, whereas the outer of said eyelets or grommets seek an intermediate position varying with the degree of tension applied by the turn-buckle 8, whereby the respective straps are always evenly tensioned.

Or, the grommets 14 may be replaced by staple-like eye-forming elements 15, as shown in Figs. III and IV, wherein all parts previously explained are indicated by like reference characters with a prime exponent to obviate repetitive description, said elements having the prong portions 16 pierced through the ends of straps 13' at 17, with their terminal-portions retroverted

and clinched over at 18, as readily understood by those conversant with the art.

In applying the furniture-brace 7 to the legs 5, or 5', at the desirable position it will be readily apparent that one tie-rod 10, or 10', is passed through one of the eye portions of one of the screws 9, when the terminal-hooks 12 are engaged by the grommets 14 or loop portions of the staple-like elements 15, in the respectively associated straps 13, or 13'. A similar procedure couples up the other tie-rod 10, or 10', whereupon the turn-buckle 8 is rotated, in an obvious manner, to tighten up the device 7 to the requisite degree. Incidentally, it is to be particularly remarked that by forming the tie-rods 10 rigid, with the median and terminal angles of the respective degrees hereinbefore specified that a well and evenly balanced tension is applied to each leg 5; as by coaction of the grommets 14 or elements 15 with the terminal-hooks 12, or 12', said grommets or elements 15 will automatically draw the respective straps 13, or 13', into "taut" engagement with the legs 5. Furthermore by using "sail" or analogous fabric for the straps 13, or 13', and tinting or otherwise coloring the same to match or blend with that of the chair legs the brace 7 does not mar the appearance of the chair, neither will said fabric straps 13, or 13' disfigure the finish of furniture to which said brace may be applied. In brief the brace 7 of this invention can be applied without the slightest damage to the legs 5 and tensioned to the requisite degree with a minimum

of time and effort, and when once adjusted the chair, or other article of furniture, will be found rigid and balanced whereby the respective legs are securely tightened and cannot spread, or work loose, relative to the supported structure.

Having thus described our invention, we claim:

1. A furniture-brace, for application to the legs thereof, comprising a turn-buckle having eye-screws; complemental rigid tie-rods engageable through the eye portions of said screws in reverse relation, each said rod including a median angle of approximately one-hundred-and-twenty degrees and having the terminal ends bent to each define an angle approximately half that of said median angle; and fabric straps with eyelet means for hook engagement on the angled portion of the respective tie-rod terminal ends with maintenance of said eyelet means relatively separated whereby uniform bracing action is applied to the several legs by rotation of the turn-buckle.
2. A furniture-brace as defined in claim 1, wherein each fabric strap is preferably made of "sail" cloth, and metallic grommets are fitted proximate the ends of said strap.
3. A furniture-brace as defined in claim 1, wherein each fabric strap is provided at the ends with staple-like elements defining eyelets, and said elements have the prong portions pierced through said strap and retrovertedly-clinched thereto.

SALVATORE DI GRADO.
CHARLES C. GRECO.
